KNITTING MACHINE

Karl Richard Lieberknecht, Oberlungwitz, Germany, assignor to Kalio, Inc., New York, N. Y., a corporation of New York

Application August 20, 1937, Serial No. 160,098
In Germany August 28, 1936

15 Claims. (Cl. 66—82)

The present invention relates to improvements in driving and control mechanism for flat full-fashioned hosiery knitting machines, and more particularly to improvements in power and manual connections for driving the main cam shaft of the machine.

In machines of the general type herein disclosed, the main cam shaft extending along the length of the machine, is driven from a drive shaft which is located in parallel relation thereto, and has a plurality of separate driving connections to the cam shaft spaced along the length of the machine to prevent undesirable torque strains and consequent inaccuracy of the cam shaft in operation. With the usual construction of these machines, the drive shaft above referred to, driven from a suitable source of power such as an electric motor, is mounted on the front portion of the machine, and has secured thereto at spaced intervals along its length, hand wheels which are used for turning over the machine by hand.

It is a principal object of the present invention to provide a novel and improved cam shaft drive well adapted for power and manual operation which is constructed and arranged to eliminate from the front side of the machine, all rapidly moving parts which might hamper or result in injury to the operator serving the machine.

It is a further object of the invention to provide a cam shaft driving and control mechanism of this general description having embodied therein braking means operative during power operation of the machine to bring the cam shaft to a quick stop without, however, interfering with the manual turning over of the machine independently of the power operating means.

With these and other objects in view, as may hereinafter appear, a principal feature of the invention consists in the provision of a drive shaft which is located in the machine parallel to the cam shaft and well removed from the operating station at the front of the machine, a manual driving element for turning over the cam shaft which is located on the front side of the machine for convenient operation by the operator, and a control element to disconnect the manual drive connections whereby the manual drive connections may stand idle during power operation of the cam shaft.

Another feature of the invention consists in the provision of braking means operable automatically in stopping the power operation of the machine, to stop the cam shaft, and thereafter to permit a free movement thereof under the

influence of the above-mentioned manual driving connections.

The several features of the invention consist also in the devices, combinations and arrangement of parts hereinafter described and claimed, which together with the advantages to be obtained thereby, will be readily understood by one skilled in the art from the following description taken in connection with the accompanying drawing, in which Fig. 1 is a view in left end elevation, illustrating particularly the power and manual driving connections for the cam shaft, only so much of the machine having been disclosed as is believed necessary to show the connection of the present invention therewith; Fig. 2 is an enlarged detail view looking from the left, illustrating a brake for stopping the cam shaft, and the connections for manually rotating the cam shaft; and Fig. 3 is an electrical diagram illustrating particularly the electrical connections for operating the solenoid brake of the machine.

The machine disclosed in the drawing as embodying in a preferred form the several features of applicant's invention, comprises a multiple section flat full-fashioned knitting machine of ordinary description, having spring beard needles movable as a unit with relation to a fixed press edge 12, yarn measuring sinkers 14, and knock-over bits (not shown).

The several cooperating instrumentalities of the machine are driven through mechanism which may be of ordinary description, from a main cam shaft 16 extending throughout the machine length and supported at intervals in bearings formed in a series of transverse frames 18 rigidly connected by the usual rear rail 20, sinker rail 22 and work table 24 extending the length of the machine. As best shown in Fig. 1 of the drawing, the machine is driven by means of an electric motor 26 mounted on a motor bracket 28. A pinion 30 secured to the armature shaft 32 of the motor 26 meshes with a gear 34 on a drive shaft 36 which is located on the machine frame parallel to and to the rear of the cam shaft 16. The drive shaft 36 in accordance with the usual practice in machines of this description, extends throughout the machine length, and operates through separate driving connections spaced along the machine length to impart rotational movement to the cam shaft 16. These connections comprise gears such as that indicated at 38 secured to the shaft 36, and arranged to mesh with pinions 40 on the cam shaft 16. A pair of such gears 38 and 40 is preferably provided at each end of the machine, and may also be

mounted in the middle of the machine to eliminate undesirable torque strains on the heavily loaded cam shaft 16. With this construction and arrangement of the driving connections for the 5 cam shaft 16, it will readily be seen that all rapidly moving parts of the driving mechanism are well removed from the operating station at the front of the machine, and thus eliminate all danger of injury to the operator when working at 10 the machine.

In accordance with the present invention, drive 15 connections are provided which are normally idle during power operation of the machine, but may be readily thrown into operation by the operator 15 when the machine is stopped for turning the machine over by hand. In the preferred form of the invention illustrated in the drawing, the manual driving connections for the cam shaft 16 comprise a hand wheel shaft 42 which takes the 20 place of the usual hand wheel shaft on these machines, having mounted thereon at spaced intervals along the machine length, hand wheels 44. A bevel gear 46 secured to the hand wheel shaft 42, meshes with a gear 48 on a rearwardly 25 extending shaft 50 which is supported to turn in bearings 52 in a supporting arm 54 loosely pivoted on the hand wheel shaft 42. The shaft 50 is provided at its rear end with a bevel gear 56 which is arranged to mesh with a bevel gear 58 on 30 a stub shaft 60 carried in bearings on the rear end of the supporting arm 54. A pinion 62 also secured to the cross shaft 60, is arranged to mesh with the driving gear 34 on the drive shaft 36.

The lever arm 54 carrying the driving connections above set forth, is normally held in a raised inoperative position during power operation of the machine, in which the pinion 62 is 35 out of engagement with the driving gear 34 by means of connections including a pendant lever 40 64 carried on a fixed pivot 66, and having formed in the lower end thereof a slot 68 to receive a pin 70 secured to the lever arm 54. The position of the lever arm 64 is controlled to cause the pin 70 to ride from one end to the other of 45 the slot 68, and thereby to move the pinion 62 into or out of engagement with the driving gear 34 by means of a control rod or link 72 slidably supported at its forward end in a bearing lug 74, and at its rear end secured to the lever 64. A knob 76 formed on the forward end of the 50 link 72, provides a convenient means for moving the link 72 forward or back to engage or disengage the hand feed connections.

55 Further in accordance with the present invention, a mechanical braking device is provided which operates automatically in stopping the driving motor 26, to brake the cam shaft 16 to a quick stop, and is thereafter released to permit 60 subsequent manual turning over of the machine. As best shown in Fig. 2 of the drawing, an internal friction brake is provided which comprises an internal friction surface 80 formed in one of the driving gears 34, and two cooperating 65 brake shoes 82, 84 supported at their upper ends on a stationary pivot 86 carried on the machine frame. A tension spring 88 tends to move the brake shoes 82, 84 toward one another to release the brake. At their lower ends the 70 brake shoes engage against opposite sides of a cam block 90 supported to turn on a stationary pivot 92 on the machine frame. Operation of the cam block 90 to set the brake, is controlled by means of a lever arm 94 secured to turn with the block 90, and connected at its free end 75

through a link 96 to the armature 98 of a brake solenoid 100.

The operation of the brake solenoid 100 is controlled through electrical connections which are operative during the operation of the motor 5 26 to de-energize the solenoid 100 and thereby 10 to permit the release of the brake under the influence of the spring 88, and rendered operative in stopping the motor 26 to momentarily 15 energize the brake solenoid 100, so that the brake 10 is applied for a sufficient length of time to stop the cam shaft 16, being then released to permit 20 manual turning over of the cam shaft. The electrical connections controlling the operation of the motor 26 and brake solenoid 100 as shown 15 in Fig. 3 of the drawing, comprise a standard starting and stopping switch 102 having the usual start push button 104 and stop button 106 which 20 controls the operation of a magnetic starting and stopping switch generally indicated at 108 25 for the motor 26. The motor 26 is driven from a three-phase power line having line connections L1, L2 and L3. The brake solenoid 100 is rendered operative when the motor 34 is de-energized through the operation of the starting 25 and stopping switch 108, to set and thereafter 30 to release the brake, by means of a solenoid brake time switch 110 having electrical connections 112 and 114 to line wires L1 and L2 extending between the motor switch 108 and the 35 motor 26. The time switch 110 as best shown in Fig. 2 of the drawing, comprises a switch plunger 116 having spring switch arms 118 and 120 connected respectively by wires 122 and 124 to the solenoid brake 100, and arranged to engage with cooperating contact members 126 and 128 which are connected respectively through wires 130 and 132 with line wires L1 and L2 on the line side of the starting and stopping switch 108. During the operation of the motor 26, the 40 switch plunger 116 is maintained in a fully raised position by means of a solenoid 134 energized by means of the connecting wires 112 and 114. When the motor switch 108 is moved to stop position by the pressing of the stop 45 button 106 to de-energize the motor 26, the solenoid 134 is simultaneously de-energized, allowing the switch plunger 116 to move downwardly under the influence of two tension springs 136, 138 connected between a cross piece 140 on the 50 plunger and stationary points on the machine, thus closing an electric circuit through the contacts 118-126 and 120-128 to energize the motor solenoid 100. The continued downward movement of the plunger 116 then causes the 55 switch contacts 118, 120 to snap past the contacts 126, 128 to again disconnect the solenoid 100, operating to again release the brake.

The time during which the brake solenoid 100 is permitted to remain energized, may be readily 60 determined by controlling the rate of the downward movement of the switch plunger 116. In the preferred form of applicant's device illustrated, a dash pot 142 is provided, which is arranged to permit a relative rapid movement of 65 the plunger 116 downwardly to a point in which the circuit is closed to energize the brake solenoid 100, and thereafter a relatively slower movement of the plunger 116 which causes the contacts to remain closed during a sufficient length 70 of time to enable the braking action to effectively stop the cam shaft 116. The dash pot provided, is of the pneumatic type, and comprises a piston 144 which is secured to the lower end of the plunger 116, and is arranged to slide within the 75

dash pot cylinder 142. An air outlet 146 in the cylinder 142 permits a relatively rapid downward movement of the piston 144 and plunger 116 from the fully raised operative position shown in Fig. 2, to a point at which contacts 118-126 and 120-128 are closed to energize the brake solenoid 100. At this point the outlet 146 is closed, and the continued downward movement of the piston 144 and plunger 116 proceed at a slower rate which is determined by the setting of an escape valve 148 in the lower end of the dash pot cylinder 142. As the plunger 116 now approaches the lower limit of its down movement, the switch contact arms 118, 120 snap past the contacts 126, 128 to again de-energize the brake solenoid 100. A check valve 150 is arranged to permit air to enter the cylinder freely, and thus to permit the plunger 116 and piston 144 to move upwardly into operating position when the switch solenoid 134 is energized in the starting of the motor 26. In order to prevent the energizing of the brake solenoid 100 with the consequent setting of the brake in starting the motor 26 as the plunger 116 is moved upwardly to its operative position, the upper sides of each of the contact members 118, 120 are preferably insulated.

Applicant's cam shaft driving and braking mechanism above described, provides an easy and accurate means for controlling the power operation of the machine, and more particularly for stopping the cam shaft in any desired position. Applicant's improved construction in which the drive shaft is moved from the front to the back of the machine, and in which the manual control is disconnected during power operation, has the advantage of eliminating any danger that the operator may be injured by this shaft which is driven at a relatively high speed, and also eliminates any danger that the goods being knitted on the machine will be injured by contact therewith. The driving and braking mechanism is also well adapted to produce a relatively slow power operation of the cam shaft. This effect may be produced by alternatively switching the motor on and off, causing an alternate application of power and braking impulses to produce a slow rotation or inching of the cam shaft.

It will be understood that the invention is not limited to the specific embodiment shown, and that various deviations may be made therefrom without departing from the spirit and scope of the appended claims.

What is claimed is:

1. Driving and control mechanism for a flat full-fashioned hosiery knitting machine having a main cam shaft extending lengthwise of the machine, which comprises a drive shaft located in the machine parallel to and rearwardly of the cam shaft, driving connections between the drive shaft and cam shaft, a power drive for the drive shaft, a manual drive element for turning the cam shaft located on the front side of the machine for convenient operation by the operator, and means to disconnect the manual drive element so that it may stand idle during the power operation of the cam shaft.

2. Driving and control mechanism for a flat full-fashioned hosiery knitting machine having a main cam shaft extending lengthwise of the machine, which comprises a drive shaft located in the machine parallel to and rearwardly of the cam shaft, driving connections between the drive

shaft and cam shaft, a power drive for the drive shaft, a hand wheel shaft extending lengthwise along the front side of the machine for convenient operation by the operator, connections therefrom for turning the cam shaft, and means to disconnect the hand wheel shaft so that the hand wheel shaft may stand idle during power operation of the cam shaft.

3. Driving and control mechanism for a flat full-fashioned hosiery knitting machine having a main cam shaft extending lengthwise of the machine, which comprises a drive shaft located in the machine parallel to and rearwardly of the cam shaft, driving connections between the drive shaft and cam shaft, a power drive for the drive shaft, manual driving connections for the cam shaft comprising a manual drive element for turning the cam shaft located on the front side of the machine for convenient operation by the operator, gearing for connecting said manual drive element with the drive shaft, and means for disconnecting said gearing whereby the manual drive element may stand idle during power operation of the cam shaft.

4. Driving and control mechanism for a flat full-fashioned hosiery knitting machine having a main cam shaft extending lengthwise of the machine, which comprises a drive shaft located in the machine parallel to and rearwardly of the cam shaft, driving connections between the drive shaft and cam shaft, a power drive for the drive shaft, a manual drive element for turning the cam shaft located on the front side of the machine for convenient operation by the operator, connections from said drive element comprising a rearwardly extending shaft, gear connections between said actuating shaft and drive shaft, a support for said actuating shaft movable to disengage said gears, a lever having a cam and slot connection with said support, and a manually operable control for moving said lever to disconnect the gears and thereby to render said manual drive element inoperative.

5. Driving and control mechanism for a flat full-fashioned hosiery knitting machine having a main cam shaft extending lengthwise of the machine, which comprises a drive shaft located in the machine parallel to the cam shaft, driving connections between the drive shaft and cam shaft, a motor connected to the drive shaft, a friction brake for stopping the cam shaft, switch connections for starting and stopping the motor, a brake actuating solenoid, and electrical connections thereto controlled from said switch connections in stopping the motor to apply the brake, and thereafter to release the brake while the motor remains stopped.

6. Driving and control mechanism for a flat full-fashioned hosiery knitting machine having a main cam shaft extending lengthwise of the machine, which comprises a drive shaft located in the machine parallel to the cam shaft, driving connections between the drive shaft and cam shaft, a motor connected to the drive shaft, a friction brake for stopping the cam shaft, switch connections for starting and stopping the motor, a brake actuating solenoid, and electrical connections controlled from said switch connections in stopping the motor to apply and thereafter to release the brake while the motor remains stopped.

7. Driving and control mechanism for a flat full-fashioned hosiery knitting machine having a main cam shaft extending lengthwise of the machine, which comprises a drive shaft located in

- the machine parallel to the cam shaft, driving connections between the drive shaft and cam shaft, a motor connected to the drive shaft, a friction brake for stopping the cam shaft, switch connections for starting and stopping the motor, a brake solenoid, a time switch for said brake solenoid, and electrical connections controlled from said motor switch connections in stopping the motor for actuating said time switch to apply the brake and subsequent to the stopping of the machine to release the brake while the motor remains stopped.
8. Driving and control mechanism for a flat full-fashioned hosiery knitting machine having a main cam shaft extending lengthwise of the machine, which comprises a drive shaft located in the machine parallel to the cam shaft, driving connections between the drive shaft and cam shaft, a motor connected to the drive shaft, a friction brake for stopping the cam shaft, switch connections for starting and stopping the motor, a brake solenoid, a time switch for said brake solenoid comprising a switch solenoid and connections operative in starting the motor for energizing said switch solenoid to set the time switch, and in stopping the motor to de-energize the solenoid to actuate the time switch, time switch contacts rendered operative upon actuation of the time switch to energize the brake solenoid, and thereafter to de-energize the brake solenoid, and a dash pot operable to retard the operation of the time switch.
9. Driving and control mechanism for a flat full-fashioned hosiery knitting machine having a main cam shaft extending lengthwise of the machine, which comprises a drive shaft located in the machine parallel to the cam shaft, driving connections between the drive shaft and cam shaft, a motor connected to the drive shaft, a friction brake for stopping the cam shaft, switch connections for starting and stopping the motor, electrical connections controlled from said switch connections in stopping the motor to apply and thereafter to release the brake while the motor remains stopped, a manual driving element for turning the cam shaft located on the front side of the machine for convenient operation by the operator, and connections therefrom for turning the cam shaft, and a control element operable to disconnect said manual driving element whereby said manual driving element may stand idle during power operation of the cam shaft.
10. Driving and control mechanism for a flat full-fashioned hosiery knitting machine having a main cam shaft extending lengthwise of the machine, which comprises a drive shaft located in the machine parallel to the cam shaft and well removed from the operating station at the front of the machine, driving connections between the drive shaft and cam shaft, a power drive for the drive shaft, braking means operable in stopping the machine to apply said braking means to stop the cam shaft and thereafter to disengage said
- braking means while the cam shaft remains stopped, a manual drive element for turning the cam shaft located on the front side of the machine for convenient operation by the operator, and connections therefrom for turning the cam shaft, and a control element operable to disconnect said manual drive element whereby said manual driving element may stand idle during power operation of the cam shaft.
11. Driving and control mechanism for a flat knitting machine, which comprises power means for driving the machine, a manually rotatable element for turning over the machine, connections independent of said power means for connecting said control element to manually turn over the machine, and means for disconnecting said element to render the same stationary when the machine is operated by power.
12. A driving and control mechanism for a flat full-fashioned hosiery knitting machine having a main cam shaft extending lengthwise of the machine, which comprises power driving connections for the cam shaft, manually operable connections independent of said power connections for manually turning the cam shaft, said manually operable connections having provision for disconnection of said manually operable connections to render the same stationary when the machine is being driven by power.
13. Driving and control mechanism for a flat full-fashioned hosiery knitting machine having a main cam shaft extending lengthwise of the machine, which comprises a drive shaft located in the machine parallel to and rearwardly of the cam shaft, driving connections between the drive shaft and the cam shaft, a power drive for the drive shaft, a manual drive element independent of said power actuated parts, and means for operatively disconnecting the manual drive element to cause said manual drive element to remain stationary when the machine is driven by power.
14. Driving and control mechanism for a flat knitting machine, which comprises power driving means for the machine, braking means for the machine, means acting when rendered operative to disconnect said power driving means and to apply said braking means to stop the machine, said acting means being operative to release the brake when the machine has stopped.
15. Driving and control mechanism for a flat knitting machine, which comprises power driving means for the machine, means to connect and to disconnect said power drive to start and stop the machine, a friction brake for stopping the machine, a brake solenoid, and a time switch for said brake solenoid comprising a switch element movable to energize and thereafter to de-energize the brake solenoid, and a dash pot for controlling movement of said switch element, and means connected to be actuated by said power drive disconnecting means to actuate said time switch.

KARL RICHARD LIEBERKNECHT.
